Patented June 8, 1915.

UNITED STATES PATENT OFFICE.

HERMAN J. BARSNESS, OF BLACK EARTH, WISCONSIN.

CATTLE-STANCHION.

1,142,135.

Specification of Letters Patent.

Patented June 8, 1915.

Application filed January 14, 1914. Serial No. 812,169.

To all whom it may concern:

Be it known that I, HERMAN J. BARSNESS, a citizen of the United States, residing at Black Earth, in the county of Dane and State of Wisconsin, have invented a new and useful Cattle-Stanchion, of which the following is a specification.

My invention relates to improvements in cattle stanchions in which one animal may be released or an entire row released simultaneously as desired, and the objects of my invention are to provide a cheap and desirable arrangement, a positive and safe method and a means for holding the cattle in a compact portable position and allowing the greatest possible freedom of action.

I attain these objects by the mechanism shown in the accompanying drawing in which—

20 Figure 1, is a front elevation in two positions, solid lines representing the closed position and dotted lines the open position. Fig. 2, is an end view with the bow turned to the left extreme position which is approximately 80°, Fig. 3, is a front view of the metal top of the bow and its coöperating parts, and Fig. 4, is a plan or top view of one section of my device with the individual releasing hasp thrown out of engagement, shown by dotted lines.

Similar numerals refer to similar parts throughout the several views.

The sill, 1, the uprights, 2, and the ribbons 3, form the frame of my device. The sill 35 being secured to the floor, the uprights are spaced and mortised into the same and the ribbons are disposed on each side of the upper ends of the uprights, then bolted through them between each pair of uprights.

40 To the left of the center a round hole is bored through the sill to receive the trunnion 5, projecting downward from the metal cross bar 4, which carries the lower ends of the upright bars, 10 and 12. The bar, 10, 45 being rigidly secured at right angles by means of the brace, 11, and the bar 12, being pivotally connected to allow the bow to be opened at the top, reference being had to Fig. 1. At the top of bar 10, is disposed

50 a casting 7, and at the top of bar 12, is fastened a similar casting 6, the two castings being adapted to unite midway between the said bars and form the upper trunnion, which being in vertical alinement with trunnion 5, permits the bow to swing approximately 160°. The casting 6, is curved

upward from the bar 12, for a distance and terminating in a semi-circular vertical neck to near its top and then projecting to the left completing the circle and forming a 60 round cap on top of which is an integral pin, adapted to pass through the centrally located elongated aperture in hasp 19.

The casting 7, attached to the top of the bar 10, is similar in form to the casting 6, 65 and extends upward forming the left half of the upper trunnion, to a point sufficiently below the cap on casting 6, to permit one prong of link 8, to be inserted through a hole in the top. The said link 8, comprising 70 a round rod disposed upon block 9, and being bent downward at right angles at both ends. The front end disposed within the hole in the top of casting 7, and the rear prong passing downward through a hole in the block 9, 75 thereby securing and holding the said casting and block in operative relation to each other. The end of the block 9, is shaped to form a half bearing for the trunnion when the two castings 6 and 7, are together and 80 secured by the hasp 19. Spaced along the top of the ribbons 3, are straps 18, provided with eyes through their outer ends through which passes a rod 17. On said rod 17, is hingedly disposed the hasp 19, which is 85 secured in position by a set collar between the knuckles on said hasp. Said hasp comprising a lower flat base plate provided with a centrally located elongated aperture adapted to drop over the loose member of 90 the cattle securing bow, and two angular wings, integral therewith and extending upward from said plate for the purpose of allowing the said hasp when lying flat on the top rail to raise up and drop over the 95 loose member of the bow when said bow comes in contact with said angular wings. A distance from the aforementioned hasp is a pin 16, secured to the rod 17. The said pin being operatively connected to one end 100 of the rod 15, the other end of said rod 15, is pivotally connected to a right angle lever 14. The horizontal arm of said lever 14, at its front end being pivotally secured to strap 13, which is disposed across the top 105 of the ribbons 3. The horizontal arm of lever 14, between centers, is equal to one half of the throw necessary to open and close the bows of my stanchion, therefore, in either position, the centers being in alinement with the rod 17, any force applied to the rod would cause no movement of the 110

lever 14, said lever being locked in both extreme positions.

The operation of my stanchion is as follows:—When it is the desire of the operator to open the entire series of stanchions, the lever 14, is moved upward causing the rod 15, to move to the right and carrying with it the hasps or latches 19, which are hingedly disposed on said rod and secured 10 in position on said rod by means of the set collars between the knuckles of said hasps as hereinbefore described. Said hasp 19, being in engagement with the loose member of the bow it is obvious that a right-hand movement of the lever and the rod co-operating therewith will cause the loose member of the bow to move in the same direction thereby opening the bow and releasing the cattle. Individual stanchions may 20 be opened by raising the hasp 19, from engagement with the loose stanchion member which will allow the bow to open independent of the series. The hasp 19, being constructed as hereinbefore described with 25 two angular wings extending upward therefrom it is obvious that when said hasp is lying flat on the top rail that the loose member of the bow when coming in contact with said angular wings will cause said hasp to raise and drop over the loose member, thus locking the two members together and allowing the entire series to be operated by the lever 14.

Having thus fully described my invention 35 I claim as new and my own and desire to secure by Letters Patent—

1. In a cattle stanchion comprising a frame, spaced uprights and a bow for securing the cattle, a plurality of straps disposed

on top of the frame and extending forward 40 thereof, apertures in the outer ends of said straps, a rod extending through said apertures longitudinally of the frame, a plurality of hasps or latches spaced along the rod and hingedly mounted thereon, set collars 45 between the knuckles of said hasp adapted to secure said hasp in position on said rod, angular wings extending upward from said hasps adapted to raise said hasps when the loose member of the cattle securing bow 50 comes in contact therewith, and closing over said loose member when its upper extension coincides with an aperture in the bottom of said hasps.

2. In a cattle stanchion, the combination 55 with a sill, spaced uprights and top ribbons forming a frame, a bow for securing the cattle, a casting attached to the stationary stanchion member and extending upward and forming the left half of the upper trunnion to a point sufficiently below the cap 60 on the right half of the upper trunnion, to permit the insertion of one prong of a link through a hole in the top of said casting, a link comprising a rod disposed upon a block 65 and bent downward at right angles at both ends, the front end disposed within a hole in the top of said casting and the rear prong passing downward through a hole in said block thereby holding the said casting and 70 block in operative relation to each other, substantially as described.

In testimony whereof I affix my signature in the presence of two witnesses.

HERMAN J. BARSNESS.

Witnesses:

J. E. HEFFERMAN,
SOPHRONIA M. MCKENZIE.
